2,642,313

UNITARY CONTAINER AND ATOMIZER FOR LIQUIDS

Jules B. Montenier, Chicago, Ill.

Application October 27, 1947, Serial No. 782,243

13 Claims. (Cl. 299—90)

1

My invention relates to atomizers for liquids, particularly liquid cosmetics such as perfumes, lotions, and astringent or anti-perspirant solutions, but may be utilized for a wide variety of other liquids such as medicaments, insecticides, and the like.

Such atomizers as have heretofore been known in the art, generally speaking, have comprised a suitable chamber or receptacle of a flexible or deformable material such as rubber or thin sheet metal for housing the liquid to be atomized in combination with means for causing a spray. In at least most cases, the atomizing means has protruded from the container proper, a fact which has made it difficult or cumbersome to ship or store the container and atomizing means as a unit.

In accordance with my invention, the combination package or container and atomizer presents the outward appearance of an ordinary bottle, there being no protuberances so far as the atomizer mechanism is concerned, and said package serves as the article which is purchased by the consumer with the contents and the atomizing means previously disposed or arranged therein by the manufacturer. The package, in its particularly preferred embodiment, is made of a flexible, transparent or translucent synthetic plastic, for example, of the vinyl, methacrylate, polystyrene, or polyethylene type, particularly the latter, and, as previously pointed out, has the outward appearance of an ordinary bottle and may be packaged, handled and stored as such. It may, if desired, be made so as to be non-refillable after atomization of its contents, the atomizing aperture or opening, in such case, being made so small that liquid could not, for all practical purposes, be passed therethrough to refill the container.

The invention is illustrated in the accompanying drawings wherein:

Fig. 1 is a perspective view of a preferred outward form that the container may take for ease of handling and ejecting the liquid contents in the form of a fine spray, the closure cap being shown in removed position;

Fig. 2 is a vertical central sectional view of one embodiment of my invention;

Fig. 3 is an exploded view showing, in perspective, the parts which comprise the spray-forming construction;

Fig. 4 is a section taken along the line 4—4 of Fig. 2;

Fig. 5 is a section taken along the line 5—5 of Fig. 4;

Fig. 6 is a vertical sectional view of another and particularly preferred embodiment of my invention wherein only the spray-forming means is shown mounted in the neck of the container;

Fig. 7 is a section taken along the line 7—7 of Fig. 6;

Fig. 8 is a horizontal section of still another embodiment of my invention, similar to the embodiment of Fig. 7 but different therefrom in a detail as described hereafter.

2

Considering first the embodiment shown in Figs. 1—5, inclusive, the container 50, made of a flexible synthetic plastic, particularly of transparent or translucent character, has the configuration shown in Fig. 1 and is provided with an exteriorly threaded neck 51 and a correspondingly interiorly threaded closure cap 52. Mounted within the neck of the container in simple frictional engagement therewith is a plug 53. The plug 53 and its associated parts, preferably made of a rigid transparent to translucent synthetic plastic, of the polymerized methyl methacrylate type, is shown in detail in Figs. 3, 4 and 5. The plug 53, which has an upper flange 54 which is adapted to rest on the upper surface of the neck, has spaced cylindrical walls 56 and 57, the inner wall 57 being of a less height than the outer wall 56. The inner wall 57 defines a pocket 58 which communicates with a central conduit 59 in the top part of the plug 53 through which the spray is ejected when the device is in use. A generally cylindrical member 61 is adapted to be seated in the pocket 58 being held in position in said pocket through frictional engagement with the walls forming said pocket. The member 61 has a central extended aperture 62 which communicates with a short aperture 63 of reduced diameter at the upper part of said member 61, the latter having a grooved portion 65 cut or molded therein. The member 61 is provided with at least one flattened vertical side wall 66 and preferably, as shown, with opposite flattened vertical side walls 66 and 67. It will be seen, therefore, that with the parts in position as shown in Fig. 4, opposite air passageways 68 and 69 are provided which communicate with the passageway formed by the groove 65. Disposed within the aperture 62 is a tube 71 which is preferably made of a transparent to translucent flexible synthetic plastic and extends to adjacent the bottom of the container.

In use, with liquid in the container 50 and with the parts assembled as shown in Figs. 2 and 4, the cap 52 of course being removed, upon deforming said container by squeezing it in the hand, the liquid is forced through the tube 71 and simultaneously air within the container is forced through passageways 68 and 69. The liquid which issues through aperture 63 commingles with the air coming from opposite directions along the groove 65 and the commingled air-liquid mixture is ejected through the conduit 59 in the form of a spray, the fineness of which may be predetermined as described hereafter.

In Figs. 6 and 7, I show a particularly preferred embodiment of my invention wherein the construction is characterized by extreme simplicity and great effectiveness. As shown in these figures, the plug 80 has a top flange portion 81, a conduit 82, a cylindrical wall 83, and, spaced therefrom, a centrally apertured or channelled depending cylindrical member 84. The plug 80, cylindrical wall 83 and member 84 are preferably formed as one piece. The member 84 is provided with at least one slit and, preferably, oppositely disposed slits or radially slotted open-

ings 86 and 87 which may, if desired, extend through from the outer periphery of the member 84 to establish communication with the central aperture in said member 84. Instead of such construction, the openings 86 and 87 may be formed as grooves or channels in the member 84 with the outer wall of said member 84 being unbroken, as shown in Fig. 8, said grooves or channels being denoted by the numerals 86a and 87a. A similar groove may extend along the top part of member 84 so as to establish communication with grooves 86 and 87 and a shoulder may be provided in the upper part of member 84 against which the tube 88 may rest. Said tube 88, corresponding to the tube 71 in the embodiment of Figs. 1-5, inclusive, is held in position frictionally in the aperture in member 84. The tube 88 may be inserted into the aperture in member 84 varying distances or in fixed position against a shoulder, and it will be seen that the volume of air passing through the slotted openings 86 and 87 and thence through the conduit 82 may be fixed or readily be controlled as desired.

It will be seen, with respect to the embodiment of Figs. 6 and 7, that when the container is compressed by squeezing in the hand, the liquid is forced upwardly through the tube 88 and simultaneously air within the container is forced through the slotted openings 86 and 87. The liquid issuing from the tube 88 commingles with the air, coming from opposite sides, in the chamber portion to form an intimate mixture and the air-liquid mixture is ejected through the conduit 82 in the form of a spray the character of which may be regulated and predetermined as described hereafter.

The character of the spray as, for example, the fineness thereof and the distance to which it will be projected from the container may be controlled or regulated by a selection of particular dimensions of the air and liquid passages and spray opening and by the angular relationship at which the air and liquid streams meet prior to ejection of the mixture thereof through the spray opening. In the embodiment shown in Figs. 1-5, inclusive, for example, excellent results are obtained in spraying light liquids containing alcohol, such as colognes, or heavier liquids, such as under-arm deodorants, comprising aqueous solutions containing as high as 20% of dissolved salts such as aluminum chloride, where the conduit 59 has a diameter between about 0.004 and about 0.03 inch, the tube 71 has an inner diameter between about 0.03 and about 0.06 inch, and the air passageway has an appreciably larger cross sectional area than the conduit 59, for example, from one and one-half to three times the diameter of conduit 59.

In the embodiment of Figs. 6 and 7, excellent results are obtained where the tube 88 has an internal diameter of about 0.03 to about 0.06 inch, the conduit 82 has a diameter between about 0.004 and 0.03 inch, and the air passageways 86, 87 have an appreciably larger cross sectional area than the conduit 82. If desired, the diameter of conduit 82 and the internal diameter of tube 88 may be approximately equal, for example, about 0.03 inch.

With reference to the distance to which the spray may be thrown or ejected, this can be adjusted, as previously indicated, by the angular relationship at which the air and liquid streams meet and, to some extent also, by the number of air passageways and the cross-sectional areas

thereof in relation to the cross-sectional area of the liquid stream. Satisfactory results are obtained for most purposes if the air and liquid streams meet at an acute angle as, for example, at 50 to 85 degrees. The more acute the angle, the greater will be the length of the spray.

In the light of the foregoing description, it will be seen that my invention, as shown by the illustrative embodiments described above, is sharply distinguishable, for example, between the usual bulb atomizers which work on the suction principle and usually have a large valve to replenish the air supply. My invention makes possible, among other things, what may be characterized as a self-contained atomizer in a permanent spray bottle or container of flexible, deformable material where the fine, misty liquid or spray is produced not by suction created by air pressure but, on the contrary, by the pressure of air already in the bottle on the liquid and simultaneous through dispersion of the said air with the liquid to be atomized. The air supply is replenished through the same small opening or aperture through which the spray issues and this is accomplished rapidly without valves or complicated devices and without adverse effect on the leakproofness of the container. It is particularly desirable that the air passageways have a greater width than height and, as pointed out previously, that they have a materially greater cross-sectional area than the diameter of the spray opening to the atmosphere as such construction allows rapid replenishment of the air within the container, thus making the device immediately operative for repeated spraying operations, the walls of the container being depressed for only a very short period of time between squeezings.

Where the containers and plugs are made of a transparent synthetic plastic, to facilitate the user's location of the aperture through which the liquid spray issues from the container, I find it convenient to have the area immediately surrounding said aperture suitably colored, for example, red, blue, green or the like.

While the invention has been described in detail, the scope thereof is not to be limited except as required by the state of the art and the limitations set out in the claims.

What I claim as new and desire to protect by Letters Patent of the United States is:

1. An atomizer and closure plug shaped for disposal within the neck of a flexible bottle or like container for use of the resulting assembly as a self-contained atomizer, said plug being provided with an outer cylindrical wall and a depending hollow member spaced from said outer cylindrical wall, a generally cylindrical part having a vertical central bore therein and at least one flattened vertical side wall and a groove along its top surface, said generally cylindrical part being frictionally held within said depending hollow member, the vertical central bore of said generally cylindrical part being adapted to frictionally hold one end of a cylindrical tube, there being at least one vertical air passageway which is defined by portions of the inner wall of said hollow member and the flattened vertical side wall of said generally cylindrical part and which communicates with said groove on the top surface of said generally cylindrical part, and a spray opening in the upper part of said plug and communicating with said groove and with said hollow member.

2. An atomizer and closure plug for insertion

within the neck of a flexible container for use of the resulting assembly as a self-contained atomizer, comprising a plug body of generally inverted cup shape for insertion within the neck of the container to substantially close the same, an annular flange resting on top of said neck and a downwardly extending annular projection forming a lower generally circular socket, the said plug having a vertical spray opening substantially centrally of said socket, a second generally inverted cup shaped member frictionally supported in said socket, said second cup shaped member having two oppositely disposed exterior, vertical cut-away portions, and a top transverse groove communicating at its ends with said cut-away portions, said second cup shaped member having a liquid opening communicating with said groove and in alignment with said spray opening, said groove forming opposed restricted air passageways on opposite sides of said liquid opening and spray opening when said second cup shaped member is fully inserted in its said socket, said second cup shaped member adapted to frictionally receive a liquid carrying tube for insertion in a liquid in said container.

3. An atomizer and closure plug for insertion within the neck of a flexible container for use of the resulting assembly as a self-contained atomizer, comprising a plug body of generally inverted cup shape for insertion within the neck of the container to substantially close the same, an annular flange resting on top of said neck and a downwardly extending annular projection forming a lower generally circular socket, the said plug having a vertical spray opening substantially centrally of said socket, a second generally inverted cup shaped member frictionally supported in said socket, said second cup shaped member having two oppositely disposed exterior, vertical cut-away portions, and a top transverse groove communicating at its ends with said cut-away portions, said second cup shaped member having a liquid opening communicating with said groove and in alignment with said spray opening, said groove forming opposed restricted air passageways on opposite sides of said liquid opening and spray opening when said second cup shaped member is fully inserted in its said socket, and a liquid carrying tube for insertion in a liquid in said container, said liquid carrying tube having its upper end frictionally supported in said second cup shaped member.

4. An atomizer and closure plug for insertion within the neck of a flexible container for use of the resulting assembly as a self-contained atomizer, comprising a plug body of generally inverted cup shape for insertion within the neck of the container to substantially close the same, and a downwardly extending annular projection forming a lower generally circular socket, the said plug having a vertical spray opening substantially centrally of said socket, a second generally inverted cup shaped member frictionally supported in said socket, said second cup shaped member having two oppositely disposed exterior, vertical cut-away portions, and a top transverse groove communicating at its ends with said cut-away portions, said second cup shaped member having a liquid opening communicating with said groove and in alignment with said spray opening, said groove forming opposed restricted air passageways on opposite sides of said liquid opening and spray opening when said second cup shaped member is fully inserted in its said socket.

said second cup shaped member adapted to frictionally receive a liquid carrying tube for insertion in a liquid in said container.

5. An atomizer and closure plug for insertion within the neck of a flexible container for use of the resulting assembly as a self-contained atomizer, comprising a plug body of generally inverted cup shape for insertion within the neck of the container to substantially close the same, and a downwardly extending annular projection forming a lower generally circular socket, the said plug having a spray opening, a second generally inverted cup shaped member frictionally supported in said socket, said second cup shaped member having two oppositely disposed exterior, vertical cut-away portions, and a top transverse groove communicating at its ends with said cut-away portions, said second cup shaped member having a liquid opening communicating with said groove and with said spray opening, said groove forming opposed restricted air passageways on opposite sides of said liquid opening when said second cup shaped member is fully inserted in its said socket, said second cup shaped member adapted to frictionally receive a liquid carrying tube for insertion in a liquid in said container.

6. An atomizer and closure plug for insertion within the neck of a flexible container for use of the resulting assembly as a self-contained atomizer, comprising a plug body for insertion within the neck of the container to substantially close the same, said plug body having a lower generally circular socket, the said plug having a vertical spray opening communicating with said socket, a generally inverted cup shaped member frictionally supported in said plug socket, said cup shaped member having two oppositely disposed exterior, vertical cut-away portions, and a top transverse groove communicating at its ends with said cut-away portions, said cup shaped member having a liquid opening communicating with said groove and with said spray opening, said groove forming opposed restricted air passageways on opposite sides of said liquid opening when said second cup shaped member is fully inserted in its said socket, said second cup shaped member adapted to frictionally receive a liquid carrying tube for insertion in a liquid in said container.

7. An atomizer and closure plug for insertion within the neck of a flexible container for use of the resulting assembly as a self-contained atomizer, comprising a plug body for insertion within the neck of the container to substantially close the same, said plug body having a lower generally circular socket, the said plug having a vertical spray opening communicating with said socket, a generally inverted cup shaped member frictionally supported in said plug socket, said cup shaped member having two oppositely disposed exterior, vertical cut-away portions, and a top transverse groove communicating at its ends with said cut-away portions, said cup shaped member having a liquid opening communicating with said groove and with said spray opening, said groove forming opposed restricted air passageways on opposite sides of said liquid opening when said second cup shaped member is fully inserted in its said socket, and a liquid carrying tube for insertion in a liquid in said container, said tube having its upper end frictionally supported in said cup-shaped member.

8. An atomizer and closure plug for insertion within the neck of a flexible container for use of the resulting assembly as a self-contained atom-

izer, comprising a plug body for insertion within the neck of the container to substantially close the same, said plug body having a lower generally circular socket, the said plug having a vertical spray opening communicating with said socket, a generally inverted cup shaped member frictionally supported in said plug socket, said cup shaped member having two oppositely disposed exterior, vertical cut-away portions, said cup shaped member having a liquid opening having its upper liquid discharge end near said spray opening, means forming opposed restricted transverse air passageways on opposite sides of said liquid opening when said second cup shaped member is fully inserted in its said socket, said transverse air passageways communicating with said liquid opening and with vertical air passageways formed by said cut-away portions, said second cup shaped member adapted to frictionally receive a liquid carrying tube for insertion in a liquid in said container.

9. An atomizer and closure plug for insertion within the neck of a flexible container for use of the resulting assembly as a self-contained atomizer, comprising a plug body for insertion within the neck of the container to substantially close the same, said plug body having a lower generally circular socket, the said plug having a spray opening communicating with said socket, a generally inverted cup shaped member frictionally supported in said plug socket, said cup shaped member having at least one exterior, vertical cut-away portion, and a top transverse groove communicating at its end with said cut-away portion, said cup shaped member having a liquid opening communicating with said groove and with said spray opening, said groove forming a restricted air passageway to deliver relatively high velocity air substantially across said liquid opening when said second cup shaped member is fully inserted in its said socket, said second cup shaped member adapted to frictionally receive a liquid carrying tube for insertion in a liquid in said container.

10. An atomizer and closure plug for insertion within the neck of a flexible container for use of the resulting assembly as a self-contained atomizer, comprising a plug body for insertion within the neck of the container to substantially close the same, said plug body having a lower generally circular socket, the said plug having a vertical spray opening communicating with said socket, a generally inverted cup shaped member frictionally supported in said plug socket, said cup shaped member having a top transverse groove and a liquid opening communicating with said groove and with said spray opening, said groove forming opposed restricted air passageways on opposite sides of said liquid opening when said second cup shaped member is fully inserted in its said socket, and means, including said cup shaped member, for delivering air from above the liquid in the container to opposite ends of said restricted transverse passageway, said second cup shaped member adapted to frictionally receive a liquid carrying tube for insertion in a liquid in said container.

11. An atomizer and closure plug for insertion within the neck of a flexible container for use of the resulting assembly as a self-contained atomizer, comprising a plug body for insertion within the neck of the container to substantially close the same, said plug body having a lower generally circular socket, a generally inverted cup shaped member frictionally inserted in said

5 plug socket, means including said socket and cup shaped member forming a pair of vertical air passageways, means including said socket and cup shaped member forming a relatively restricted transverse air passageway communicating with the tops of said vertical air passageways, said cup shaped member adapted to receive a liquid carrying tube and having a liquid passageway for delivering liquid from said tube to said transverse passageway, said plug having a spray opening communicating with said transverse air passageway and with said liquid passageway.

10 12. An atomizer and closure plug for insertion within the neck of a flexible container for use 15 of the resulting assembly as a self-contained atomizer, comprising a plug body for insertion within the neck of the container to substantially close the same, said plug body having a lower generally circular socket, a generally inverted cup shaped member frictionally inserted in said plug socket, a tube extending into said cup shaped member for conveying liquid thereto, means including said socket and cup shaped member forming a pair of vertical air passageways, means 20 including said socket and cup shaped member forming a relatively restricted transverse air passageway communicating with the tops of said vertical air passageways, said cup shaped member having a liquid passageway for delivering liquid from said tube to said transverse passageway, said plug having a spray opening communicating with said transverse air passageway and with said liquid passageway, said tube having its upper end frictionally supported in said cup 25 shaped member.

13. An atomizer and closure plug for insertion within the neck of a flexible container for use of the resulting assembly as a self-contained atomizer, comprising a plug body for insertion 40 within the neck of the container to substantially close the same, said plug body having a lower generally circular socket, a liquid carrying member frictionally inserted in said plug socket, means including said socket and liquid carrying member forming a pair of vertical air passageways, means including said socket and liquid carrying member forming at least one relatively restricted transverse air passageway communicating with said vertical air passageways adjacent the top thereof, said liquid carrying member adapted to receive a liquid carrying tube and having a liquid passageway for delivering liquid from said tube to said transverse passageway, said plug having a spray opening communicating with said transverse air passageway and with said liquid passageway, the aforesaid construction serving to intimately commingle air and liquid immediately before discharge through said spray opening.
